STEERING WHEEL FOR JUVENILE VEHICLES

Charles E. Steele, Olney, Ill., assignor to American
Machine & Foundry Company, a corporation of
New Jersey

Filed Feb. 10, 1969, Ser. No. 15,706

Term of patent 14 years

Int. Cl. D12—14

U.S. Cl. D14—30

FIG. 1

FIG. 2

FIG. 3

FIG. 4

FIG. 1 is a top plan view of the steering wheel of my design;

FIG. 2 is a partly broken away side elevation view of the wheel;

FIG. 3 is a bottom plan view of the wheel; and

FIG. 4 is another side elevation view of the wheel.

I claim:

The ornamental design for a steering wheel for juvenile vehicles, substantially as shown.
